(57) **CLAIM**

The ornamental design for an electric makeup brush as shown and described.

DESCRIPTION

FIG. 1 is a front perspective view of a base for an electric makeup brush, illustrating my design thereof;

FIG. 2 is a front elevation view of the base thereof;

FIG. 3 is a rear elevation view of the base thereof;

FIG. 4 is a right side view of the base thereof;

FIG. 5 is a left side view of the base thereof;

FIG. 6 is a top view of the base thereof; and,

FIG. 7 is a bottom view of the base thereof.

The broken lines in the drawings illustrate those features of the article of manufacture that form no part of the claimed design.
